Primary Examiner — Mary Ann Calabrese(74) *Attorney, Agent, or Firm* — Sughrue Mion, PLLC(57) **CLAIM**

The ornamental design for a street advertisement display panel, as shown and described.

DESCRIPTION

FIG. 1—a front view of a street advertisement display panel showing our new design;

FIG. 2—a rear view;

FIG. 3—a right side view;

FIG. 4—a left side view;

FIG. 5—a top view; and,

FIG. 6—a bottom view.

In the drawings, the broken lines illustrate environment and form no part of the claimed design.
